UNITED STATES PATENT OFFICE.

MARCELI J. BEKSINSKI, OF CURWENSVILLE, PENNSYLVANIA.

DESIGN FOR A COMBINATION PHONOGRAPH, BOOKCASE, AND ELECTRIC LAMP.

Application filed March 6, 1926. Serial No. 16,813. Term of patent 7 years.

To all whom it may concern:

Be it known that I, MARCELI J. BEKSINSKI, a citizen of Poland, residing at Curwensville, in the county of Clearfield and State of Pennsylvania, have invented a new, original, and ornamental Design for Combination Phonograph, Bookcase, and Electric Lamp, of which the following is a specification, reference being had to the accompanying drawing, forming part thereof.

The figure is a perspective view of a combination phonograph, bookcase and electric lamp, showing my new design.

I claim:

The ornamental design for a combination phonograph, bookcase, and electric lamp, as shown.

In testimony whereof I have affixed my signature this 13th day of February, 1926.

MARCELI J. BEKSINSKI.
